RAIL JOINT

Filed June 25, 1927

UNITED STATES PATENT OFFICE.

HENRY BROWNLEE, OF PORT HOPE, ONTARIO, CANADA.

RAIL JOINT.

Application filed June 25, 1927. Serial No. 201,421.

My invention relates to improvements in rail joints, and the object of the invention is to devise simple means for readily attaching or detaching a pair of opposing rail ends 5 without the necessity of removing nuts and bolts, and in which the rail ends will be held definitely in place so that the upper surface of the rail heads will always be in perfectly flush alignment so that the rolling stock 10 will travel smoothly thereover and prevent the wearing of the rail end or the loosening of the same due to vibration, and it consists essentially of the arrangements and construction of parts as hereinafter more 15 particularly explained.

Fig. 1 is a perspective view of two abutting rail ends and my device applied thereto.

Figs. 2 and 3 are perspective views of the rail ends shown in Figure 1 separated.

Fig. 4 is a plan view of the parts shown in Figure 1.

Fig. 5 is a longitudinal sectional view through Figure 4.

Fig. 6 is a transverse section through Figure 5 taken at the meeting point between the rail ends.

Figs. 7 and 8 are perspective details of the interlocking members forming my rail joint connection.

In the drawing like characters of reference indicate corresponding parts in each figure.

1 and 2 indicate two rail ends which are supported in the usual manner upon a tie 3.

The ends of the vertical webs 1° and 2° of the rails are formed with concaved recesses 1^x and 2^x.

5 is a jaw member provided at its base with a convexed face 5^x fitting into the recess 2^x as clearly shown in Figure 5. The arms 6 and 7 of the jaw member 5 are provided with transversely aligned orifices 8 through which bolts or rivets 9 extend so as to pass through orifices 10 in the vertical web of the rail end 2. 11 is a similarly formed jaw member which is similarly secured to the rail end 1.

The inner opposing ends of the jaw members 5 and 11 are enlarged and provided with interengaging fingers. The member 5 is provided with outer arc-shaped fingers 12 and 13 projecting beyond the inner end or base of

the jaw member 5 and forming intervening arc-shaped slots 14 and 15 located at each side of the inner end of the jaw member. 53 The opposing jaw member 11 is provided with inner arc-shaped fingers 16 and 17 which when the jaw members are interengaged fit into the slots 14 and 15.

18 and 19 are curved slots formed between the fingers 16 and 17 and the outer portions 20 and 21 of the enlarged portion of the jaw member 11. 22 is a base or bed plate which extends beneath the base flange 23 of the rail end 2 and is provided with side portions 24 and 25 extending upwardly and around the lateral portions of the base flanges into contact with the vertical web. 60

The plate 22 after the members 5 and 11 have been interengaged is slid longitudinally 70 so as to bridge the joint of the rail ends 1 and 2 and pass partially onto the base flange 24^x of rail 1 so as to rest upon the upper surface of a tie 3 as indicated at Figure 1, thereby securely holding the rail ends from vertical movement providing a solid bed, and at the same time preventing any longitudinal movement between the rail ends 75 tending to separate them.

It will, of course, be understood that there is a certain amount of play provided between the fingers 12 and 13 and 16 and 17 and the sides of the slots in which they fit so as to permit of the expansion and contraction due to temperature changes. 80

From this description it will be seen that I have devised a very simple form of interlocking connection between two rail ends which will hold such rail ends securely in place so that there will be no displacement 90 of the rail end due to vibration and the consequent wearing of the rail ends, and at the same time dispensing with nuts and bolts which must be detached in order to separate the rail ends. 95

What I claim as my invention is:—

1. The combination with a pair of abutting rail ends, of a jaw member fitting the vertical web of each rail end and extending longitudinal from the end thereof, curved fingers 100 and complementary slots formed in each jaw member adapted to fit one within the other respectively, and a base or bed plate slidably carried upon the base flange of the rails

and adapted to be slid longitudinal across the meeting ends of the rails after the aforesaid fingers and slots have been interengaged.

2. The combination with a pair of abutting rail ends, having concaved recesses in the opposing ends of each rail web, a pair of jaw members, the faces of which are

adapted to fit one against the other and to fit in the recesses of the rail webs, and curved fingers and slots formed at each side of such jaw members adapted to interengage one with the other respectively to connect the rail ends together.

10

HENRY BROWNLEE.
